US0D1076657S

(12) **United States Design Patent** (10) **Patent No.:** **US D1,076,657 S**
(45) **Date of Patent:** **** May 27, 2025**

(54) **SCREW**

(71) Applicant: **KWANTEX RESEARCH INC.**,
Tainan (TW)

(72) Inventor: **Chao-Wei Lin**, Tainan (TW)

(73) Assignee: **KWANTEX RESEARCH INC.**,
Tainan (TW)

(**) Term: **15 Years**

(21) Appl. No.: **29/925,497**

(22) Filed: **Jan. 24, 2024**

(51) LOC (15) Cl. **08-08**

(52) U.S. Cl.

USPC **D8/387**

(57) **CLAIM**

The ornamental design for a screw as shown and described.

DESCRIPTION

FIG. 1 is a front, right-side and top perspective view of a screw showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dashed broken lines depict portions of the screw that form no part of the claimed design.

The break lines shown in FIGS. 1-5 symbolize breaks in the of the article in which the claimed design is embodied. The appearance of any portion of the article between the break lines forms no part of the claimed design.

1 Claim, 6 Drawing Sheets
